Attorneys

UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed January 17, 1925. Serial No. 3,008.

To all whom it may concern:

Be it known that I, HAROLD G. WARR, a citizen of the United States, residing at Park Ridge, in the county of Cook and State 5 of Illinois, have invented certain new and useful Improvements in Rail Anchors, of which the following is a specification.

This invention relates to rail anchors, and more particularly to an improved one-piece 10 anchor formed from a single continuous bar of metal, which, when applied to the rail, will maintain a firm grip on the upper and lower surfaces of the base of the rail by spring pressure.

One object is to provide an improved anchor of this type, which will include a downwardly bowed tie engaging portion, which will bear against the tie a substantial distance below the top surface thereof. The 15 anchor comprises a spring jaw portion at one end of the tie-engaging bow, which grips one side flange of the rail base, and an upset portion at the other end of the bow for engaging the bottom and side of the rail- 20 edge at the opposite side of the rail base.

Another object is to provide a rail anchor 25 of this type, having three cooperating rail-gripping portions, for engaging the upper and lower plane surfaces of the rail base at spaced points, which permit the anchor to adapt itself to rails varying slightly in proportions and size, and having somewhat rough or irregular surfaces.

A further object is to provide an anchor 30 of this type which can be easily driven onto the rail by blows applied at a convenient angle to one end of the anchor.

A further object is to provide improved 35 means for engaging one edge of the rail base to limit the movement of the spring-jaw onto the rail-base flange.

Further objects and advantages of this 40 invention will be apparent from the following detailed description of one approved form of the invention.

In the accompanying drawings:

Fig. 1 is a side elevation of the anchor in applied position on the rail, which latter is shown in transverse vertical section.

Fig. 2 is a plan view of the anchor in applied position.

Fig. 3 is an end elevation of the anchor in applied position on the rail.

Fig. 4 is a partial side-elevation, similar

to Fig. 1, showing a modified form of the means for the limiting movement of the spring jaw transversely onto the rail.

At 1 is shown the rail, having a base portion 2 which rests upon a series of ties, one of which is indicated at 3. 50 The rail anchor is formed of a single continuous bar of metal, of substantially rectangular cross section, bent to form two bowed portion 3 and 4, which have one end 5 of each in common. The bar 55 is bent back rather sharply at 4 to form a short arm 6, and a long arm 3 forming the larger bowed portion hereinbefore mentioned. The inner free end portion of short arm 6 has an inclined flat face at 7, to form 60 an engaging member for the upper plane surface 8 of one flange 9 of the rail base. The inner surface of the small bow 4 is curved as at 10 to encircle but not have a gripping engagement with, the edge portion 11 of rail 65 base flange 9. The curved portion 10 extends to the bearing face 12 on the common end 5 of the large and small bows 3 and 4. The bearing 12 is adapted to engage the 70 plane lower surface of rail base 2 at a point 75 spaced from the rail edge 11, but nearer this rail edge than the bearing point of rail-engaging face 7 upon the upper surface 8 of the rail flange. The free end portion 13 of the long arm 3 is provided with a bearing 80 portion 14 adapted to engage the lower surface of the rail base adjacent the edge of the opposite rail base flange 15. The distance 85 between the upper bearing surface 7 of the anchor and the plane of the lower bearing 90 surfaces 12 and 14, is such that the smaller bowed portion 4 of the anchor will have to be flexed or sprung when this portion of the anchor is forced onto the rail base flange 9. Since the downwardly pressing upper end 95 bearing 7 of the anchor is located between the lower bearing surfaces 12 and 14, when the small bow is stretched apart by forcing the anchor on to the rail base, the spring action will tend to throw the opposite end bearing 14 up against the base of the rail base flange 15. The end 13 is upset to form 100 a lug 16, which snaps into engagement with the edge of the flange 15 to hold the anchor securely in place upon the rail base.

When the anchor is to be applied to the rail, the small arm 6 is hooked over one flange 9 of the rail base, with the long arm

3 extending substantially transversely beneath the rail base. The hook or bowed portion 4 is then driven onto flange 9 by blows struck with a suitable implement substantially in the direction of the arrow A in Fig. 1, so that the bearing portions 7 and 12 are forced inwardly along the upper and lower surfaces of the flange 9 until lug 16 snaps into place against the edge of the opposite rail base flange 15, with the third bearing portion 14 bearing against the lower plane surface of the rail base adjacent the edge of this flange 15. This operation will cause the arms 6 and 3 to be flexed or sprung apart so that the rail base flange will be securely gripped between the bearing portions 7, 12 and 14, and the lug 16 will hold the anchor in place and prevent it slipping from the rail, in the direction toward the left in Fig. 1.

As will be noted in Fig. 1, a slight clearance 17 will normally remain between the lower edge of rail-base flange 9 and the adjacent inner surface 18 of the curved portion 10 of the anchor, when lug 16 is in close engagement with the opposite edge of the rail-base. In other words, the distance between surface 18 and the inner vertical surface of lug 16 is somewhat greater than the normal width of the rail-base, to permit application of the anchor to rails varying slightly in this dimension. However, when the anchor is being driven onto the rail, the inner surface 18 of curve 10 will come into engagement with the edge of rail-base flange 9 after lug 16 has snapped into place, to limit the movement of the anchor in this direction, and prevent overflexing of the spring jaw 4.

Furthermore, if the anchor tends to become canted or inclined appreciably from its normal position substantially perpendicular to the center-line of the rail, one edge or the other of the anchor at 18 will engage the adjacent edge-portion of the rail-base flange and cooperate with lug 16 to limit this canting movement. Obviously, the lug 16 will prevent the anchor working back toward the left, Fig. 1, further than to the position shown in that view, with a possible clearance 17 between the anchor and the rail-base flange.

In the anchor partially illustrated in Fig. 4, a lug 19 is provided on the inner face of the curved portion 10, having a substantially vertical face 20 for engaging the vertical edge portion 11 of the rail-base flange 9. This stop-lug functions substantially the same as the surfaces 18 previously described, but provides a greater rail-engaging surface and a more positive limiting action.

This anchor may be constructed from standard bar material by simple forging operations. It remains of substantially uni-

form cross section from end to end, and is formed with substantially continuous and easy curves, with no sharp or abrupt bends, so that the strength and elasticity of the material are not impaired at any point. Since the anchor has only a three point gripping contact with the rail, consisting of the spaced bearing surfaces 7, 12 and 14, the anchor may be fitted to rails varying slightly in size and configuration, and having somewhat rough or irregular surfaces on the rail base flanges. The large downwardly bowed portion 3 forms an extensive bearing surface against the adjacent side of the tie, and extends a substantial distance down along the side of the tie to insure a firm and secure engagement therewith and prevent breaking off or chipping the upper edge of the tie, and to prevent the anchor from riding up over the tie, which might occur if the anchor engaged only the upper edge portion of the tie.

I claim:

1. A rail-anchor formed of a single continuous bar of metal comprising a downwardly bowed portion adapted to extend beneath the rail-base and engage the tie, and a hooked end portion extending from one end of the bowed portion and adapted to be flexed about one rail-base flange and engage the upper and lower surfaces thereof so as to hold the other end of the bowed portion in engagement with the bottom surface and vertical edge of the other rail-base flange.

2. A rail-anchor formed of a single continuous bar of metal comprising a downwardly bowed portion adapted to extend beneath the rail base in engagement with the side of the tie, and in engagement with the lower surface of the rail-base at its ends, a hooked portion extending upwardly and inwardly from one end of the bow, and a lug extending upwardly from the other end of the bow, the hooked portion being adapted to be flexed about one rail-base flange so as to hold the other end of the bow in engagement with the lower surface of the other rail-base flange, and the lug engaging the vertical edge of this latter rail-base flange to lock the hooked portion in flexed engagement with the rail.

3. A rail-anchor formed of a single continuous bar of metal comprising a downwardly bowed portion adapted to extend beneath the rail base in engagement with the side of the tie, and in engagement with the lower surface of the rail-base at its ends, a hooked portion curved first downwardly, then upwardly, and then inwardly from one end of the bow, and a lug extending upwardly from the other end of the bow, the hooked portion being adapted to be flexed about one rail-base flange so as to hold the other end of the bow in engagement with the lower surface of the other rail-base

- flange, and the lug engaging the vertical edge of this latter rail-base flange to lock the hooked portion in flexed engagement with the rail.
5. A rail anchor formed of a single continuous bar of metal bent upon itself to form a long arm and a short arm, there being rail-engaging surfaces on the end of the short arm and near the base of the long arm 10 adapted to engage respectively the upper and lower surfaces of one rail-base flange so as to swing the free end of the long arm upwardly, the bases of both arms remaining out of gripping relation with the adjacent 15 edge of the rail base, and means on the free end of the longer arm for engaging the opposite vertical edge portion of the rail-base.
5. A rail anchor formed of a single continuous bar of metal bent upon itself to 20 form a long arm and a short arm, there being a surface on the end of the short arm adapted to engage the upper surface of one rail-base flange, and a surface on the inner portion of the long arm near its base adapt- 25 ed to engage the lower surface of this rail-base flange at a point nearer the edge of the rail-base but spaced therefrom, and means on the free end of the long arm for engag- 30 ing the opposite edge portion of the rail-base.
6. A rail anchor formed of a single bar of metal, and comprising a downwardly bowed portion adapted to extend beneath the rail and engage the bottom face of the rail-base 35 adjacent either side thereof, an upwardly and inwardly bent arm on one end adapted to extend around one edge portion of the rail-base and be flexed in its application to the rail so as to engage the upper surface 40 of the base flange at a point spaced from the edge thereof and hold the long arm up against the rail base, and upturned means on the opposite end of the bar engaging the opposite vertical edge of the rail-base.
7. A rail anchor formed of a single bar of metal, and comprising a downwardly bowed portion adapted to extend beneath the rail and engage the bottom face of the rail-base adjacent one edge thereof, and at a point 50 spaced from the opposite edge, an upwardly projecting lug at the first mentioned end of the bar adapted to engage the first edge of the rail-base, and an upwardly and inwardly extending arm on the other end 55 of the bar adapted to encompass the second edge of the rail base, and be flexed when driven onto the rail so that the upper end portion of the arm grips the upper surface of the rail-base flange.
8. A rail anchor formed of a single bar of metal, and comprising a downwardly bowed portion adapted to extend beneath the rail and engage the bottom face of the rail-base adjacent one edge thereof, and at a point 60 spaced from the opposite edge, an upwardly 65 projecting lug at the end of the bar adapted to engage the first mentioned edge of the rail-base, and an upwardly and inwardly extending arm on the other end of the bar adapted to encompass the second edge of the rail base, and be flexed when driven onto the rail so that the upper end portion of the arm grips the upper surface of the rail-base flange, at a point nearer the center line of the rail than the point of contact of the lower bar portion with the bottom face of the rail flange.
9. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 70 ing the bottom and vertical edge of the other rail-base flange, and the smaller bowed portion encircling the first mentioned flange with its other end engaging the upper surface of this flange.
10. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 75 ing the bottom and vertical edge of the other rail-base flange, and the smaller bowed portion encircling the first mentioned flange with its other end engaging the upper surface of this flange.
11. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 80 ing the bottom and vertical edge of the other rail-base flange, and the smaller bowed portion encircling the first mentioned flange with its other end engaging the upper surface of this flange.
12. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 85 ing the bottom and vertical edge of the other rail-base flange, and the smaller bowed portion encircling the first mentioned flange with its other end engaging the upper surface of this flange.
13. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 90 ing the bottom and vertical edge of the other rail-base flange, and the smaller bowed portion encircling the first mentioned flange with its other end engaging the upper surface of this flange.
14. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 95 ing the bottom and vertical edge of the other rail-base flange, and the smaller bowed portion encircling the first mentioned flange with its other end engaging the upper surface of this flange.
15. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 100 ing the bottom and vertical edge of the other rail-base flange, and the smaller bowed portion encircling the first mentioned flange with its other end engaging the upper surface of this flange.
16. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 105 ing the bottom and vertical edge of the other rail-base flange, and the smaller bowed portion encircling the first mentioned flange with its other end engaging the upper surface of this flange.
17. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 110 ing the bottom and vertical edge of the other rail-base flange, and the smaller bowed portion encircling the first mentioned flange with its other end engaging the upper surface of this flange.
18. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 115 ing the bottom and vertical edge of the other rail-base flange, and the smaller bowed portion encircling the first mentioned flange with its other end engaging the upper surface of this flange.
19. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 120 ing the bottom and vertical edge of the other rail-base flange, and the smaller bowed portion encircling the first mentioned flange with its other end engaging the upper surface of this flange.
20. A rail anchor formed of a single bar of metal comprising two bowed portions having one end in common, this end adapted to engage the bottom surface of one rail-base flange at a point spaced from the edge thereof, the larger bowed portion extending beneath the rail-base with its other end engag- 125 ing the bottom and vertical edge of the other rail-base flange, and the smaller bowed portion encircling the first mentioned flange with its other end engaging the upper surface of this flange.

- flange adjacent its edge, and the smaller bowed portion encircling the first mentioned flange with its other end engaging the upper surface of this flange, at a point intermediate the points of engagement of the other two ends with the bottom surface of the rail-base and a lug on the first mentioned bar end adapted to engage the adjacent rail-base edge and hold the smaller bowed portion in flexed gripping engagement with the opposite rail-base flange.
13. A rail anchor formed of a single continuous bar of metal and comprising a long arm adapted to underlie the rail base and having two spaced rail-engaging portions one near each end of the arm, and a short arm adapted to overlie one of the rail-base flanges and having a rail-engaging surface near its free end which cooperates with the two lower rail-engaging surfaces to grip the rail-base, and a pair of stop members, one near each end of the long arm for limiting movement of the anchor transversely of the rail in either direction.
14. A rail anchor formed of a single continuous bar of metal and comprising a long arm adapted to underlie the rail-base and having two spaced rail-engaging portions one near each end of the arm, and a short arm adapted to overlie one of the rail-base flanges and having a rail-engaging surface near its free end which cooperates with the two lower rail-engaging surfaces to grip the rail-base, and a pair of stop members, one near each end of the long arm and spaced apart a distance slightly greater than the width of the rail base for limiting movement of the anchor transversely of the rail in either direction.
15. A rail anchor formed of a single continuous bar of metal and comprising a long arm adapted to underlie the rail-base and having two spaced rail-engaging portions one near each end of the arm, and a short arm adapted to overlie one of the rail-base flanges and having a rail-engaging surface near its free end which cooperates with the two lower rail-engaging surfaces to grip the rail-base, and a pair of upturned portions, one at each end of the long arm for engaging the edges of the rail-base and limiting movement of the anchor transversely of the rail.
16. A rail-anchor formed of a single continuous bar of metal having three spaced rail-gripping surfaces, two of which are adapted to be sprung into engagement with the upper and lower surfaces respectively of one rail-base flange in such a manner as to hold the third surface in spring-pressed engagement with the opposite rail base flange and a shoulder engaging the vertical edge of this latter rail-base flange to lock the anchor in position on the rail.
17. A rail-anchor formed of a single continuous bar of metal having three spaced rail-gripping surfaces, two of which are adapted to be sprung into engagement with the upper and lower surfaces respectively of one rail-base flange, at points out of vertical alignment whereby the twisting action thereby imparted to the anchor will hold the third gripping surface in engagement with the opposite rail-base flange and a shoulder engaging the vertical edge of this latter rail-base flange to lock the anchor in position on the rail.
18. A rail-anchor formed of a single continuous bar of metal bent to form a jaw at one end thereof, there being three spaced rail-gripping surfaces on the anchor, two of which are within the jaw and adapted to be sprung into engagement with the upper and lower surfaces of one rail-base flange at points spaced from the edge thereof, these two gripping surfaces being so relatively disposed as to hold the third gripping surface, which is adjacent the other end of the anchor in spring pressed engagement with the opposite rail-base flange.
19. A rail-anchor formed of a single continuous bar of metal bent to form a jaw at one end thereof, there being three spaced rail-gripping surfaces on the anchor, two of which are within the jaw and adapted to be sprung into engagement with the upper and lower surfaces of one rail-base flange at points spaced from the edge thereof, these two gripping surfaces being so relatively disposed as to hold the third gripping surface, which is adjacent the other end of the anchor in spring-pressed engagement with the lower surface of the opposite rail-base flange.
20. A rail-anchor formed of a single continuous bar of metal bent to form a long arm extending below the rail-base, and a short arm extending over one rail-base flange, there being two spaced rail-gripping surfaces on the long arm, one adjacent each end thereof, and a third gripping surface on the short arm, located above and between the first two gripping surfaces, and adapted together with one of the lower surfaces to be sprung into gripping engagement with the respective upper and lower surfaces of one rail-base flange, and thereby hold the third gripping surface in spring-pressed engagement with the other rail-base flange and means adjacent this third gripping surface for engaging the vertical edge of the rail base.

HAROLD G. WARR.
